LINOLEUM OR SIMILAR ARTICLE

Albert J. Pucci, Brooklyn, N. Y., assignor to Fibreboard
Paper Products Corporation, San Francisco, Calif., a corporation of Delaware

Application December 3, 1957, Serial No. 48,756

Term of patent 14 years

(Cl. D92—17)

The figure is a plan view of a piece of linoleum showing my design. The broken lines outline a design unit which is repeated in regular succession as indicated by the extensions beyond the boundaries of such unit.

I claim:

The ornamental design for a linoleum or similar article, substantially as shown and described.
